CLAIM

The ornamental design for a cleaning fluid tank for carpet extractor, as shown and described.

DESCRIPTION

FIG. 1 is a perspective view of a cleaning fluid tank for carpet extractor showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof; and,

FIG. 7 is a bottom plan view thereof.

The parts shown in broken lines in FIG. 1 are shown for illustrative purposes only and form no part of the claimed design.
